COATING SHEET MATERIAL

Stanley J. Johnson, Portland, Maine, assignor to
S. D. Warren Company, Boston, Mass., a cor-
poration of Massachusetts

Application June 11, 1938, Serial No. 213,275

14 Claims. (Cl. 91—33)

This invention relates to methods of and apparatus for coating sheet material. The invention is applicable to the coating of woven or felted fabrics, paper, sheets of rubber or other resinous material, films of regenerated cellulose or of cellulose esters or ethers, and other sheet material of similar nature.

A widely used method of coating flexible sheet material is that disclosed by Lebel in U. S. Patent No 1,980,923. That method, in brief, comprises applying a fluid coating composition to one side of a flexible web, and then supporting the reverse side of the coated web while it is carried past an air jet or "air brush" which extends across the width of the web and is directed at the coated surface directly opposite the point of support. The air jet smooths the layer of fluid coating composition. It may actually cut away part of the coating, which has been applied in excess, leaving a predetermined residual quantity which it redistributes, evens and smooths on the web in a uniform layer. This method yields a very excellent coated product but it is limited to coating only one side of the web at a time, owing to the fact that the back of the web must be supported while the air jet is acting on the freshly coated side. The smoothing of a coating by means of an air jet without the use of rigid means for supporting the web against the jet is not regarded as feasible at present. Otherwise it would be a simple matter to coat both sides of a web and then smooth both sides in a single pass by means of air jets. The use of one air jet as the supporting means for another air jet also is not regarded as being feasible at present.

By coating only one side of the paper at a time I mean coating only one side of the paper in a single pass of the web from a source such as a reel, through the coating operation and a drying operation.

Another method of coating paper which is capable of yielding an excellent coated product is one in which fluid coating composition is smoothed on the surface of the web by a driven roll which contacts the coated surface with a wiping action. In this method the coating may be both applied to and smoothed upon the web by the wiping roll or it may be applied in some other suitable way and then only smoothed by the wiping roll. Preferably the web is supported and held against the smoothing or wiping roll by means of a backing roll. In such a set-up it is apparent that only one side of the web can be coated at a time. It is possible, however, to do away with the backing roll, and to hold the pa-

per in contact with the smoothing roll by bending the web around it under tension. In such a case it is practically necessary that the paper shall have a considerable arc of contact with the smoothing roll in order to insure that every spot on the paper surface shall actually be contacted. Otherwise "skips" or uneven spots may occur on the coated surface. Thus it is seen that there is unavoidable a considerable frictional drag on the paper, since the latter must be held firmly against the roll but yet at the same time must slip over a considerable portion of the roll surface. Nevertheless, paper of fair strength can be smoothed or coated and smoothed satisfactorily by this method, particularly if the pull between the smoothing roll and the first succeeding tension means is comparatively short. It would appear feasible, and it has been proposed, to coat and smooth both sides of a web in a single operation by using two such wiping or smoothing rolls without backing rolls placed on opposite sides of the web one ahead of the other so that both rolls do not contact the web at the same point. It is apparent, however, that such practice doubles the frictional drag on the paper and consequently, while it is possible to carry out the method experimentally in the case of strong paper, the method has not proved to be generally practicable for production use at ordinary commercial operating speeds. Hence, for practical purposes, roller-coating of this nature still remains a one-side coating process. Coating both sides of the web in a single pass by providing smoothing rolls on opposite sides of the web, each holding the web against the other is, so far as I am aware, not practically possible with equipment available at present.

The two comparatively new coating methods, i. e., the air brush method and the roll-coater method, are both generally considered to yield coated paper of a quality superior to that produced by the older, double brush-coaters of conventional type. Moreover, both new methods are capable of operating at considerably higher speeds than the old brush-type coaters can attain. Consequently the newer types of coaters applied as one-side coaters are able to, and do, compete successfully with the older type double-coaters. It is apparent, however, that a modification of either the air brush method or the roll-coater method or some combination of them which would achieve satisfactory coating of both sides of the web in a single operation and at the speeds now commonly used for those methods in one side operation, would result in an advanta-

geous increase in speed of production with a corresponding decrease in production cost. The present invention accomplishes this desirable result.

It is an object of the present invention to provide improvements in methods of manufacturing sheet material coated on both sides in a single operation.

Another object is to provide a method of coating sheet material on both sides in a single operation which involves the use of two rectilinear substantially non-divergent air jets.

Another object is the provision of a method of holding a web of sheet material bearing a layer of mobile coating composition against a rigid smoothing device by means of air pressure.

Another object is the provision of a method of holding one side of a web of sheet material bearing a coating on both sides against a rigid smoothing device by means of an air jet which also serves to smooth the other side.

Another object is to provide, in a method of coating sheet material on both sides in a single operation, the improvement comprising smoothing the coating on one side by means of an air jet and on the other side by means of a roll, the air jet serving to hold the web against the roll and the roll serving to support the web against the jet.

Another object is to spread coating on one side of a sheet by an air jet and on the other side by a rigid scraper or blade.

Another object is to provide new combinations of apparatus for the accomplishment of the aforesaid objects.

Other objects and advantages will appear hereinafter.

Broadly, the invention resides in the use of an air jet for holding a coated web of sheet material against a rigid device, either a roll or scraper, which serves to smooth the coating and may also serve to apply coating and more specifically the rigid device may also serve to support the web against the air jet while the latter serves to smooth a coating on its side of the web.

The coated sheet is dried in any suitable manner, as on an air-floater or in a tower or tunnel and the sheet is then finished as desired.

Fig. 1 is a diagrammatic showing of the essential parts of one embodiment of the invention.

Fig. 2 is a diagrammatic showing of a second embodiment of the invention.

Fig. 3 is a diagrammatic showing of a modification of the apparatus illustrated in Fig. 2 in which the scraper 21 of Fig. 2 is replaced by a roller.

Fig. 4 is a diagrammatic showing of a portion only of the apparatus illustrated in Fig. 1 in which the air jet 10 is replaced by a roller.

In Fig. 1 a web 1, for example a web of paper, with its two sides indicated as A and B respectively, is unwound from reel 2, passed over guide and tensioning rolls 3, 3 and passed with side A in contact with roll 4 which turns in a vat 5 containing fluid coating composition. Roll 4 is driven, by means not shown, at a speed which permits the application of the web of the desired weight of coating composition, usually an amount somewhat in excess of that desired on the finished paper. The web then passes with side B in contact with guide-roll 6 and past air-nozzle 11 which emits a rectilinear, substantially non-divergent jet of air against coated side A, thus smoothing the coating on side A and removing the excess coating, if any. Roll 7, contacting

side B of the web, acts as a backing-roll to support the sheet while the air jet from nozzle 11 is acting on side A. Roll 7 also carries a film of coating composition which it transfers to side B of the web at the point of contact therewith. Fluid coating composition is applied to roll 7, preferably in excess, by roll 8 which turns in vat 9, containing the coating mixture. The coating on roll 7 is spread and smoothed, the excess if any being removed in the process, by a rectilinear, substantially non-divergent air jet from nozzle 10. The web, now coated and the coating spread and smoothed on both sides, is carried to a suitable drier 12 in which the coating is dried sufficiently not to be marked before it contacts guide roll 13. The web is dried further in its passage to guide-roll 14, and is then wound up on reel 15.

Air-nozzles 10 and 11 may be constructed according to the disclosure of the co-pending application of K. E. Terry, Serial No. 78,235, now Patent No. 2,139,628. In the above described embodiment any suitable means may be substituted for roll 4 for applying coating to side A of the web and instead of applying coating to the side B of the web by means of roll 7, coating may be applied by any other suitable means and roll 7 may serve merely as a smoothing means or application of coating to side A may be omitted in which event jet 11 would serve merely to hold the web against the smoothing roll 7. Roll 7 may rotate in a direction opposite to the direction of the web travel or it may rotate in the same direction but with a peripheral speed different from the lineal speed of the web.

According to the modification of the invention shown in Fig. 2, a web 1 with sides A and B is passed between squeeze rolls 16 and 18 which leave a limited quantity of fluid coating composition on both sides of the web. The coating composition is supplied to side A by roll 16 which turns in vat 17 containing the coating mixture. Coating composition is supplied to side B by pipe 19, near the entrance to the nip between 16 and 18. The web is carried past air-nozzle 20 which emits a rectilinear substantially non-divergent air jet that smooths the coating on side A, preferably removing the excess therefrom, and that likewise pushes the sheet into firm contact with the rigid blade or scraper 21. Blade 21 smooths the coating on side B, preferably removing excess coating therefrom, and likewise serves to support the web while the air jet from 20 acts thereon. The web, coated and smoothed on both sides, is then dried and finished in any conventional way.

In this modification it is apparent that if coating is not applied to side A, the jet 20 will serve merely to hold the web against the scraper 21 while it serves to smooth the coating on side B. It is likewise apparent that rolls 16 and 18 may be replaced by any other suitable means for applying coating and that the coating composition may be applied to the two sides either simultaneously or at different times as desired and also that the composition applied may be the same or different on the two sides. In the modification of the apparatus illustrated in Fig. 3 it will be seen that the roller 22 occupies the same relative position to the remainder of the apparatus as the scraper 21 in Fig. 2 and serves the same purpose, i. e. to support the web against the jet 20 and to smooth coating on side B of the web.

When a roll is used both as applicator and smoothing means as in the case of the roll 7 in

Fig. 1, it is preferred to use an air brush to spread the coating upon the said roll. Nevertheless, in many cases fairly satisfactory results may be obtained by use of a rigid doctor means, e. g., a blade or another roll, in place of the air brush 10. The substitution of a roller, i. e. the roller 23, for the air brush 10 is illustrated in Fig. 4.

In the set-up shown in Fig. 1, the air jet from nozzle 11 fulfills two entirely distinct functions. First it performs its usual known action of spreading and smoothing the mobile coating upon the side of the web which it contacts. Besides this, the air jet cooperates with the smoothing means on the reverse side of the sheet, i. e., roll 7, by pushing the web throughout its entire width firmly against the rigid smoothing device. The latter function of the air brush is found to be very useful, even in cases where the side of the web contacted by the air jet is not coated. The pressure of the air jet pushes the web firmly against the opposed smoothing means, making unnecessary extra tension to hold the sheet in contact with the smoothing means. The air jet makes it possible for the opposed smoothing means to spread and smooth the coating satisfactorily even when the web makes substantially only a line contact with the smoothing means. Thus may be avoided all frictional drag caused by a sharp bend of the web about the smoothing means and contact of the web with excessive area of the smoothing means.

The rigid smoothing means 7 in Fig. 1, or 21 in Fig. 2, likewise has two distinct functions to fulfill. First it smooths the mobile coating on the side of the web which it contacts; secondly it also serves as the supporting means required to back up the web while the air brush is acting on the other side.

Thus it is seen that in either the arrangement of Fig. 1, or the arrangement of Fig. 2, there is double cooperation between the air smoothing means and the rigid smoothing means. For instance, air brush 11 of Fig. 1, and air brush 20 of Fig. 2, each has a primary function and a secondary function, and coating-roll 7 of Fig. 1, and scraper 21 of Fig. 2, also each has a primary function and a secondary function. The primary function of each smoothing means, of course, is to smooth the coating on the side of the web on which it acts. Each means, however, is assisted in the accomplishment of its primary smoothing function, by the cooperating action of the opposed means as the latter performs its secondary supporting function. Specifically, in Fig. 1, the air from nozzle 11 has for its main purpose the smoothing of the coating on side A of the web; the air jet is enabled to accomplish this purpose, however, only because of the support given by roll 7 on the opposite side of the web. Conversely, coating roll 7 spreads and smooths the coating on side B of the web as its chief function, but it is assisted in this action by the air pressure from nozzle 11 which pushes the web firmly against roll 7.

The particular arrangement of apparatus shown in Fig. 1, produces a practical equivalent of a web coated and smoothed on both sides by the use of an air brush. One of the outstanding advantages of the air brush method of coating is that a coating of uniform thickness can be applied irrespective of considerable possible variation in thickness or uniformity of surface of the base stock. In the same way it is found that a uniform layer of coating composition can be spread upon the surface of an applicator roll by

use of an air brush in spite of minor possible imperfections in the roll itself. Hence a uniform layer of coating may be spread on coating-roll 7 of Fig. 1, and the coating may be transferred uniformly to a web contacting the roll, since the air jet from nozzle 11 acts to push the web against the roll 7, making the web follow the contour of the roll even if considerable variation in diameter may exist therein at various points along its length.

It will be seen that the invention makes possible the production in a single operation of two-side coated paper of the highest quality at speeds comparable to those now used for making one-side coated papers. Besides this obvious advantage, it is believed that the fact that both sides are coated before drying, makes the penetration of the coating composition the same on both sides of the sheet, and tends to decrease likelihood of trouble from curling of the finished sheet.

The invention likewise provides a new arrangement of apparatus, employing two air brushes, by which paper or other sheet material may be coated on both sides simultaneously. An important feature of the invention is a method of holding a coated web against a rigid smoothing device by means of air pressure.

I claim:

- 30 1. A method of coating a web of flexible sheet material on both sides in a single operation comprising continuously advancing the web; applying mobile coating composition to one side of the web, rigidly supporting the reverse side of the web against a solid surface while subjecting the mobile coating on the first side directly opposite said surface to the action of a rectilinear, substantially non-divergent air stream, whereby the coating composition is spread and smoothed on said first side; simultaneously applying mobile coating composition to the surface and spreading and smoothing said coating thereon by means of a second rectilinear, substantially non-divergent air stream and moving the surface in contact with the web whereby the layer of coating thereon is transferred to the second side of said web, and drying the coated web.
- 35 2. A method of coating flexible webs on both sides comprising continuously advancing the web, applying mobile coating composition to the two sides of the web; substantially simultaneously smoothing the coating on the two sides by subjecting the coated web on one side to the action of a rigid smoothing surface and on the other side to the action of an air jet, the surface and the air jet being substantially directly opposed to each other on opposite sides of the web, and drying the so-coated web.
- 40 3. In a method of smoothing mobile coating composition upon a flexible web by means of a rigid smoothing surface the improvement comprising urging the web against said smoothing surface by means of an air jet.
- 45 4. A method of coating paper on both sides in which a paper web is continuously advanced, mobile coating composition is applied to the two sides of the web, the mobile coating composition is spread and smoothed substantially simultaneously on the two sides, on one side by an air jet and on the other by a rigid surface.
- 50 5. Apparatus for coating flexible sheet material comprising means for continuously advancing a web of the material, means for applying coating to at least one side of the web, rigid means contacting said side of the web for smoothing said
- 55
- 60
- 65
- 70
- 75

coating, and an air jet positioned to urge the web toward said smoothing means.

6. Apparatus as defined in claim 5 in which the smoothing means is a scraper.

7. Apparatus as defined in claim 5 in which the smoothing means is a roll.

8. Apparatus for coating a flexible sheet material comprising means for continuously advancing a web of the material, a rotating roller contacting the web with a wiping action, means for applying coating to the roller, means for smoothing the coating on the roller, and a free air jet positioned to urge the web against the roller.

9. Apparatus as defined in claim 8 in which the means for smoothing the coating on the roller is a free air jet.

10. Apparatus for coating flexible sheet material comprising means for continuously advancing a web of the material, means for applying coating to both sides of the web, rigid means contacting the web for smoothing the coating on one side thereof, and an air jet positioned to urge the

web against said rigid means and also serving to smooth the coating on the other side of the web.

11. Apparatus as defined in claim 10 in which the rigid smoothing means is a scraper.

12. Apparatus as defined in claim 10 in which the rigid smoothing means is a roller.

13. Apparatus for coating flexible sheet material comprising means for continuously advancing a web of the material, a rotating roller contacting one side of the web, means for applying coating to the roller, means for smoothing the coating on the roller, means for applying coating to the other side of the web and an air jet positioned to urge the web against the roller and to smooth the coating on said other side of the web.

14. Apparatus for coating flexible sheet material comprising means for continuously advancing a web of the material, a roller for applying coating to one side of the web and smoothing the coating thereon by a wiping action and an air jet positioned to urge the web against said roller.

STANLEY J. JOHNSON.
